DESIGN FOR A PLASTIC BASKET

John Fiedler and Joseph Fiedler, Dayton, Ohio

Application April 9, 1947, Serial No. 138,264

Term of patent 7 years

(Cl. D58—4)

To all whom it may concern:

Be it known that we, John Fiedler and Joseph Fiedler, citizens of the United States, residing at Dayton, in the county of Montgomery and State of Ohio, have invented a new, original, and ornamental Design for a Plastic Basket, of which the following is the specification, reference being had to the accompanying drawing, forming part thereof.

In the drawing, Figure 1 is a top plan view of a plastic basket, showing our new design; Figure 2 is a side elevational view thereof; and Figure 3 is an end elevational view thereof.

We claim:

The ornamental design for a plastic basket, as shown.

JOHN FIEDLER.
JOSEPH FIEDLER.
